INVENTOR

Gabriel E Rohmer

BY C. P. Goepel

ATTORNEY

UNITED STATES PATENT OFFICE.

GABRIEL E. ROHMER, OF BROOKLYN, NEW YORK.

DRILL.

1,380,682.

Specification of Letters Patent. Patented June 7, 1921.

Application filed April 30, 1919. Serial No. 293,729.

To all whom it may concern:

Be it known that I, GABRIEL E. ROHMER, a citizen of the United States, residing in New York, borough of Brooklyn, Kings county, State of New York, have invented certain new and useful Improvements in Drills, of which the following is a specification.

This invention relates to drills, and more particularly to drills of the portable type.

My invention in its broadest aspect comprehends an improved means for securely holding the work in position to be operated upon by the drill. It is quite common in the art to employ power operated clamps for this purpose, but so far as I am advised all such clamps have proved inefficient and unsatisfactory in practical use, for the reason that these clamps being actuated by fluid pressure, such, for instance, as compressed air, depend entirely upon a constant application of a predetermined pressure to the ram in order to maintain the clamp in its effective position. As a consequence, it is evident that any diminution in the pressure will result in the recession of the clamping member from the work so that the latter will be released.

It is, therefore, the primary object and purpose of my present improvement to provide a work clamp in axial alinement with the drill and self locking power actuated means to move the work clamp to effective position and maintain the clamp in such position after the power has been cut off or diminished.

It is a further object of my invention to provide a very simple mounting and arrangement of the drill and work clamp with relation to a work rest, whereby the work may be accurately drilled and with a minimum of vibration of the several parts.

It is also an important object of the invention to provide a work holder for drills as above characterized which may be readily applied or adapted to use in conjunction with either the horizontal or vertical type of drill.

With the above and other objects in view, the invention consists in the improved combination, construction and relative arrangement of the several parts, as will be herein-after more fully described, subsequently claimed and illustrated in the accompanying drawing in which—

Figure 1 is a side elevation, partly in

section, of a horizontal drill illustrating one embodiment of the present invention.

Fig. 2 is an end elevation, partly in section.

Fig. 3 is a view similar to Fig. 1 illustrating a slightly modified form of the invention.

Fig. 4 is an elevation illustrating the invention as applied to a vertical type of drill.

Fig. 5 is an end view of the support and motor drill standard of the embodiment shown in Fig. 1.

Fig. 6 is a similar view of the form shown in Fig. 3; and

Fig. 7 is a plan view of the supporting table of the form shown in Fig. 4 and showing the machine in horizontal section.

Referring in detail to the drawing, and more particularly to Figs. 1 and 2 thereof, 75 1 designates a suitable support, which in the illustrated embodiment of my invention is in the form of a hollow tubular rod or bar. Upon one end of this support a sleeve 2 is securely fixed and a housing 2^a disposed 80 in superposed relation to this sleeve is integrally connected thereto. The function and purpose of this housing will be presently explained.

In spaced relation to the sleeve 2 a work 85 rest 3 is mounted upon the support 1, said work rest consisting of a standard having a sleeve or collar on its lower end surrounding the support. At its lower side the support is formed with a longitudinally extending channel or groove 17. A key 25 fixed in the work rest 3 is engaged in this groove to prevent turning movement of the work rest upon the support. This work rest may be securely locked in a longitudinally adjusted position on the support by means of the set screw 26.

In spaced relation to the work rest 3, the drill motor support 4 is mounted upon the main supporting rod 1, and is provided with standards 26 and 27 at its opposite ends between which the motor designated 5 is mounted. The motor shaft is provided with a chuck 15 of any suitable type in which the drill bit 14 is detachably held. The motor supporting casting is formed with a boss 19 housing a bolt on which is mounted the circular key 18 engaging the key way. A screw 20 is threaded in the boss and coacts with the collar 19 to position the same within the groove or channel 17 of the support 1 whereby the drill may

be securely held in its longitudinally adjusted position on the support with respect to the work rest 3.

One side of the housing 2^a is closed by the head 11, which is formed with a boss 11^a. Upon the opposite side wall of the housing a similar boss 9^a is formed. Within this housing a rotor member 12 is arranged, said member having spaced radially disposed 10 vanes and a central threaded bore. This bore receives the thread 9 of a screw 6, said screw being provided on one of its ends with the work clamping head 7. The lower side of the screw is formed with the keyway 14, which receives the end of a key 13 fixed in the boss 9^a. The opposite sides of the rotor member 12 are recessed to receive suitable gaskets 10, which prevent leakage of the pressure fluid from the housing. It will be 20 noted that there is a clearance between the thread of the screw and the walls of the bosses 9^a and 11^a, so that the screw will have a free rectilinear movement through the housing when the rotor member 12 is rotated.

The screw actuating member may be operated either pneumatically, hydraulically, or electrically. In the present instance I have illustrated pneumatic means for rotating the rotor member. The pressure fluid supply pipe 16 extends through a tubular rod or support 1 and branch connections 21 and 22, extending from the supply pipe and upwardly at opposite sides of the sleeve 2. 35 The upper ends of these branches extend inwardly through the wall of the housing 2^a at the bottom thereof, and each branch is equipped with a valve cock 23 and 24. The housing 2^a is provided at its top with an exhaust port 24^a for the pressure fluid.

It will be manifest from the above description that when the compressed air is let into the housing through one of the branch pipes it will impinge against the blades or 45 vanes of the rotor member and rotate the latter. As the screw 6 has a threaded connection with the member, the said screw will be moved axially and the clamping head 7 will be engaged against the work indicated 50 at 8, which has been positioned against the side of the work rest 3. This head is of hollow form as shown to receive the point of the drill bit and is provided with one or 55 more openings 29 through which the drill chips or shavings may pass. When the head has been thus tightly clamped against the work to rigidly and securely hold the latter against the work rest, the pressure fluid may be cut off. The clamping head will not 60 recede from its effective applied position in view of the fact that this head is positively locked against such movement by reason of the screw connection with the rotor member 12. Thus the work cannot possibly move or 65 shift during the drilling operation.

In Fig. 3 of the drawing I have illustrated a slightly modified form of the invention, wherein the supporting rod 30 is formed with a flattened lower face 40. The work rest 38 is fixed in adjusted position by means 70 of the set screw 39, which engages the face 40. The drill motor 34, which may be either of the compressed air or electrically actuated type, is mounted between the standards 32 of the supporting casting 31 which is slidably engaged upon the rod 30. The standard 32 is provided with a socketed hand hold 32^a. This casting is fixed in its longitudinally adjusted position by means of the screw 39^a, holding the collars 39^b tight around the supporting rod. As in the above described form of the invention, the drill 36 is secured in a suitable chuck 35.

At the relatively opposite side of the work rest 38, an elongated cylindrical housing 42 85 is arranged and is integrally connected with the sleeve 41 mounted on the rod 30, the said sleeve being securely fixed to the rod by one or more bolts or screws indicated at 50. The work clamping head 44 in this embodiment 90 of my invention is swiveled upon the reduced end 43^a of the screw 43. The screw threads 49 are engaged with the complementary threads formed in the bores of the bosses 41^a and 41^b on the opposite ends of the housing 95 42. Within this housing the rotor member 45 is arranged and fixed by means of the key 48 to an intermediate section of the screw 43. At opposite sides of the intermediate portion 100 of the rotary wheel I provide the series of helicoid vanes respectively designated 46 and 47, which extend in reverse directions to enable right and left rotary motion on the outer periphery of the rotor member. The piston rings 45^a are provided for the tight 105 and non-leaking performance at each side of the rotor member.

The pressure fluid is supplied to the opposite ends of the housing through a tube 56, extending from a suitable source of supply, 110 which is connected to one end of a pipe 55 fixed in a depending lug 41^c on the sleeve 41. Branch pipes 51 and 53 extend upwardly from the pipe 55 and are equipped with the cut-off valves 52 and 54 respectively. These pipes extend through the opposite end walls of the housing 42.

In the operation of the modified construction above described, it will be apparent that when the pressure fluid is admitted to 115 one end of the housing 42, the rotor member 45 therein will be rotated by the action of the pressure fluid against one series of the helicoid vanes. This member being fixed upon the screw 43, the latter will be 120 rotated, and by reason of its threaded engagement in the ends of the housing 42 a rectilinear movement will be imparted thereto. The clamping head 44 is thus quickly 125 brought into engagement with the work 130

piece 37 arranged against the side of the work rest 38. As the clamping head is swiveled on the screw, the screw may continue to rotate after the head is thus engaged with the work, so that the desired clamping pressure may be obtained. This head, which is hollow, is provided in its wall with the outlet openings 57 for the drill chips.

- 10 In either form of my invention above described, it will be readily seen that the clamping head, after it is effectively engaged with the work, is securely locked or held in such position while the supply of 15 pressure fluid to the rotor member housing is completely cut off. The drill and the work rest may be easily and quickly adjusted relative to each other upon the common support and the drill bit positioned into 20 axial alinement with the work clamping head.

In Fig. 4 of the drawing I have illustrated an embodiment of my invention as applied to a vertical type of drill. In this 25 arrangement the work rest in the forms above referred to is dispensed with, and in lieu thereof a work support 63 is mounted upon a rectangular extension 73 on the upper end 64 of the vertically disposed screw 30 62, which is movable through the housing 61, mounted on the frame 60, as at 65, by either of the fluid pressure actuated means 35 which I have hereinbefore described. For this purpose a channeled plate or guide 74 is fixed to the under side of the support 63 to receive the extension 73. This support is also provided with extensions 72, which coact with the machine frame to 40 guide the support in its vertical movement. The pressure fluid is supplied to the opposite ends of the housing 61 through pipes 75 and 77, which are equipped with the cut-off valves 76 and 78 respectively.

The drill 67 held in the chuck 68 is actuated through the medium of the shaft 69, which is provided on its upper end with a beveled gear 70, with which a complementary gear 71 is engaged. The latter gear is driven through the medium of a belt 50 71 or other equivalent means. 66 indicates the work piece arranged on the support 63 and which is maintained in proper engagement with the drill by the upward movement of the screw 62 actuated 55 by the pressure controlled means within the housing 61, the continued upward movement of the support causing gradual penetration of the drill.

From the foregoing description taken in 60 connection with the accompanying drawing, the construction and manner of operation of each of the illustrated embodiments of my invention will be clearly and fully understood. Without greatly complicating devices which have heretofore been devised

for the accomplishment of a similar purpose I have succeeded in producing a thoroughly practical and efficiently operating work clamp for use in connection with portable drills. The various parts of the device are of relatively simple form, not liable to get out of order and may be manufactured and assembled at relatively small cost.

70 While I have herein illustrated and described several alternative forms of the invention which I have found to be very satisfactory in practice, it is nevertheless to be understood that the invention may likewise be exemplified in many other constructions, and I accordingly reserve the privilege of 75 adapting all such legitimate changes as may be fairly embodied within the spirit and scope of the invention as claimed.

I claim:

1. In a drilling apparatus, a support, a 85 drill mounted upon said support, a housing secured on the support, a part movable through said housing and having work engaging means on one of its ends, fluid actuated means engaged upon said part within 90 the housing to axially move said part and effectively engage the work-engaging means with the work, and means associated with said part adapted to automatically establish and maintain a positive locking action 95 to prevent retrograde movement thereof and positively lock the work holding means in its effective position.

2. In a drilling apparatus, a support, a 100 drill mounted upon said support, a housing secured on the support, a part rectilinearly movable through the housing and having work engaging means on one of its ends, and a rotary fluid actuated rotor member mounted within the housing and coacting 105 with said movable part to cause a rectilinear movement thereof in the rotation of said rotor member and effectively engage the work holding means with the work.

3. In a drilling apparatus, a support, a 110 drill mounted upon said support, a housing secured on the support, a part rectilinearly movable through the housing and having work engaging means on one of its ends, and a rotary field actuated rotor member 115 mounted within the housing and coacting with said movable part to cause a rectilinear movement thereof in the rotation of the rotor member and effectively engage the work holding means with the work, the coacting means between said part and the rotor member acting to positively lock said part against retrograde rectilinear movement when the rotor member is stationary, and thereby maintain the work engaging 120 means in its effective position.

4. In a drilling apparatus, a support, a 125 drill mounted upon said support, a housing secured on the support, a screw rectilinearly movable through the housing and having 130

work engaging means on one of its ends, and a rotor member mounted within the housing and having threaded connection with said screw whereby the screw is moved in the rotation of the rotor member to engage said work engaging means with the work, and said rotor member when stationary acting to positively lock the screw against retrograde rectilinear movement, 10 and thereby maintain the work engaging means in its effective position.

5. In combination a rectilinearly movable

work engaging member, rotary fluid actuated means for moving said member into or out of engagement with the work and 15 having means associated therewith for automatically locking said work engaging member against reverse rectilinear movement in either direction upon a diminution in the pressure influence of the fluid medium. 20

In testimony that I claim the foregoing as my invention, I have signed my name thereto.

GABRIEL E. ROHMER.
